UNITED STATES PATENT OFFICE.

AUTHOR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND.

ORDNANCE RECOIL AND RUN-OUT APPARATUS.

1,344,621.

Specification of Letters Patent. Patented June 29, 1920.

Application filed November 10, 1919. Serial No. 337,042.

To all whom it may concern:

Be it known that we, Sir ARTHUR TREVOR DAWSON and Sir GEORGE THOMAS BUCKHAM, both subjects of the King of Great Britain, residing at Vickers House, Broadway, Westminster, in the county of London, England, have invented certain new and useful Improvements in or Relating to Ordnance Recoil and Run-Out Apparatus, of which the following is a specification.

This invention relates to recoil and run-out apparatus for high angle ordnance particularly anti-aircraft ordnance, in which the load on the run-out springs or the air pressure in the air recuperator has to be very high to insure the proper run-out of the gun when firing at high angles of elevation. The chief object of the invention is to provide in an improved manner for obtaining a uniform form or approximately uniform length of recoil at all angles of elevation of the gun and uniformity or substantial uniformity in the run-out movement at all angles of elevation.

According to the present invention two conduits are provided one serving to establish liquid communication between each end of the recoil cylinder and the other serving to establish liquid communication between a recess (in which a retarding ram works) and the recoil cylinder, these conduits being controlled by valves or cocks which are moved automatically during the elevation of the gun and the said conduits and valves being employed in addition to and independently of any known or desired means for gradually cutting off the flow of liquid past the recoil or brake piston during recoil and past the retarding ram during run-out.

In order that the invention may be clearly understood and readily carried into effect, the same will be described more fully with reference to the accompanying drawings, in which—

Figures 1 and 2 are respectively a side elevation and a vertical section along the axis of the recoil cylinder showing a form of the invention as employed with the type of recoil and run-out apparatus in which the recoil piston is attached to the gun and the recoil cylinder is attached to the cradle.

Fig. 3 is a rear elevation of Fig. 1 with part thereof in section on the line 3, 3 of Fig. 1 and

Fig. 4 is a local section taken on the line 55 4, 4 of Fig. 1.

Fig. 5 is a sectional side elevation showing a form of the invention as employed with the type of recoil and run-out apparatus in which the recoil piston is attached to the 60 cradle and the recoil cylinder is attached to the gun.

Fig. 6 is a front elevation of Fig. 5, and Figs. 7 and 8 are sections taken approximately on the lines 7, 7 and 8, 8 of Fig. 5. 65

A is the recoil or brake cylinder, A' is its piston and a' is the piston rod, the said piston having a part in which works a tapered valve key a (Fig. 2) in the cylinder as is well understood or the wall of the cylinder 70 A having a tapered slot or keyway a⁰ (Fig. 5) as is also well understood. A² is the aforesaid conduit serving to establish liquid communication between each end of the recoil cylinder, and a² is the valve or cock 75 which automatically controls the passage of the liquid through this conduit. B is the retarding ram and B' is the recess in which this ram works. B² is the aforesaid conduit serving to establish liquid communication 80 between the recess B' and the recoil cylinder A and b² is the valve or cock which automatically controls the passage of the liquid through this conduit.

In the construction shown by Figs. 1 to 4, 85 the conduit A² is constituted by a passage in the wall of the recoil cylinder A and the valve or cock a² is constituted by a rotary plug which is arranged transversely at the front part of the said conduit and is formed 90 with a suitably shaped port a^{2x} as shown. The said passage A² communicates with each end of the cylinder at such points that when the gun is in the run-out position the forward end of the passage is behind the recoil 95 or brake piston as shown by full lines in Fig. 2, and when the gun is in its fully recoiled position the rear end of the passage is in front of this piston as shown by chain lines in Fig. 2. The plug a² is angularly displaced during the elevation of the gun by suitable means such as a rod A³ connected at one end to an arm a³ on the plug a² and at the other end to the gun carriage at a point some distance from the axis of the gun trunnions, in such manner as to obtain an angular movement of the plug which may be equal to or proportional to the angle of ele- 100 105

vation of the gun. The port a^{2x} is so constructed that the passage A^2 is fully open when the gun is horizontal and is completely closed when the gun is at its maximum angle 5 of elevation.

The other conduit B^2 is constituted by an axial passage in the retarding ram B, the rear end of this passage opening upon the rear face of the ram and therefore into 10 the recess B' when the ram is situated with in this recess which in the example shown is formed in the rod a' of the piston A'; the front end of this passage opens into a transverse hole in a head b^x on this ram, 15 this hole communicating with a longitudinal hole whose rear end is open at the rear face of this head. The aforesaid valve or cock b^2 is in the form of a rotary plug arranged transversely at the junction of the aforesaid 20 transverse and longitudinal holes and provided with a suitably formed port b^{2x} . This plug is automatically moved in any suitable manner during the elevation and depression of the gun and the port b^{2x} is so 25 constructed that the passage B^2 in the retarding ram is completely closed when the gun is horizontal but becomes fully open when the gun reaches the maximum angle of elevation. When the valve is completely 30 closed, the liquid can escape only through the passage provided by a tapered flat surface B^3 on the retarding ram. The retarding ram is held in position in the cylinder by a screw-threaded plug A^x in the cylinder 35 A bearing against the front surface of the head b^x to press the rear surface of the latter against a shoulder in the cylinder and the head has an axial extension B^x disposed in a recess in a nut α^x screwed into the 40 cylinder behind the plug.

The two plugs a^2 , b^2 are preferably connected together by a parallel motion linkage (see Fig. 1) so that they move simultaneously through the same angle during the 45 elevation of the gun, and it will be observed that as one of them is being opened the other is being closed and vice versa, the plug b^2 reaching the fully open position at the same time that the plug a^2 reaches its 50 fully closed position.

In the construction shown by Figs. 5 to 8, the piston rod a' is made hollow throughout its entire length to receive a rod C whose rear part is made hollow and divided into two by a screw threaded plug c to form two chambers A^2 and C^2 of which the former constitutes the conduit between the two ends of the cylinder A and the chamber C^2 forms the end of the recess B' 55 in the piston rod a' for the retarding ram B. The walls of the chambers A^2 and C^2 constitute the aforesaid valves a^2 and b^2 respectively, the wall a^2 of the chamber A^2 being formed with two ports a^{2x} , a^{2x} 60 adapted to register with ports A^{2x} , A^{2x} in the 65

piston rod a' and the wall b^2 of the chamber C^2 being formed with a port b^{2x} adapted to register with a port B^2 in the piston rod a' , this port B^2 constituting the aforesaid conduit through which liquid 70 passes from the recess B' to the cylinder A. The rod C passes through a gland C^x at the front end of the piston rod a' and is prevented from moving axially by a collar C' . The said rod is free to be moved angularly 75 about its axis and to effect this movement automatically during the elevation of the gun the end of the rod is connected to an arm C^x which is suitably connected by a link C^{1x} to a lever C^{2x} pivoted on the spring 80 case or other convenient part, this lever being connected by a rod C^{3x} to the gun carriage in an eccentric position with respect to the axis of the gun trunnions.

When the gun is horizontal the flow of 85 liquid governing the recoil is regulated by the area of the keyway a^0 and the effective areas of the ports a^{2x} , A^{2x} which are fully open in this position, the forward port A^{2x} being closed at a predetermined distance before the end of the recoil stroke by being 90 covered by the casing of the gland C^{3xx} through which the piston rod a' passes. The shape and area of the ports are so proportioned as to obtain uniformity or substantial uniformity in the run-out at all angles of elevation. When the gun is in the horizontal position and is running home the flow of the liquid from the recess B' is 95 regulated in the ordinary way by the tapered flat surface B^3 on the retarding ram B, the port b^{2x} being at this time closed. This port is fully opened when the gun is at full elevation. The shape and area of this port is so proportioned as to give approximately 100 the correct amount of retardation automatically at all intermediate angles of elevation.

What we claim and desire to secure by Letters Patent of the United States is:— 110

1. In ordnance recoil apparatus, the combination with the recoil cylinder, the recoil piston working therein, and means for gradually cutting off the flow of the liquid past the piston during recoil, of a conduit 115 in the wall of the cylinder serving to establish liquid communication between each end of the recoil cylinder and independent of the first mentioned means, a valve controlling said conduit, and means for moving said valve automatically during the elevation of the gun so as to obtain an approximately uniform length of recoil at all angles of elevation.

2. In ordnance recoil and run-out apparatus, the combination with the recoil cylinder, the recoil piston working therein, means for gradually cutting off the flow of the liquid past the piston during recoil, a retarding ram, a recess in which this ram 125 130

works and means for gradually cutting off the flow of the liquid past the retarding ram during run-out, of a conduit serving to establish liquid communication between each end of the recoil cylinder and independent of the means for gradually cutting off the flow of liquid past the piston during recoil, a valve controlling said conduit, a conduit serving to establish liquid communication between said recess and said cylinder and independent of the means for gradually cutting off the flow of liquid past the retarding ram during run-out, a valve controlling the second mentioned conduit, and means for moving said valves automatically during the elevation of the gun.

3. In ordnance recoil and run-out apparatus, the combination with the recoil cylinder, the recoil piston working therein,

means for gradually cutting off the flow of 20 the liquid past the piston during recoil, a retarding ram, a recess in which this ram works and means for gradually cutting off the flow of the liquid past the retarding ram during run-out, of a conduit serving to 25 establish liquid communication between each end of the recoil cylinder, a rotary plug valve controlling said conduit, a conduit serving to establish liquid communication between said recess and said cylinder, 30 a rotary plug valve controlling the second mentioned conduit, and means for moving said rotary plug valves automatically during the elevation of the gun.

In testimony whereof, we affix our signatures.

ARTHUR TREVOR DAWSON.
GEORGE THOMAS BUCKHAM.
